UNITED STATES PATENT OFFICE.

JAMES J. WISELOGEL, OF DETROIT, MICHIGAN, ASSIGNOR TO NATIONAL SPRING & WIRE COMPANY, OF ALBION, MICHIGAN, A CORPORATION OF MICHIGAN.

CUSHION-SEAT.

1,339,537.

Specification of Letters Patent. Patented May 11, 1920.

Application filed December 14, 1917. Serial No. 207,041.

To all whom it may concern:

Be it known that I, JAMES J. WISELOGEL, a citizen of the United States of America, residing at Detroit, in the county of Wayne 5 and State of Michigan, have invented certain new and useful Improvements in Cushion-Seats, of which the following is a specification, reference being had therein to the accompanying drawings.

10 The invention relates to cushion seats of that type in which the skirt or facing of the cushion embraces the spring frame and is secured to the base thereof. It is the object of the present invention to provide a simple 15 and inexpensive means of attaching the skirt to the base and the invention comprises the construction as hereinafter set forth.

In the drawings:

Figure 1 is a sectional perspective view 20 of a spring seat to which my improvements are applied;

Fig. 2 is a cross-section showing the manner of attaching the skirt;

Fig. 3 is a similar view showing the skirt 25 attached; and

Fig. 4 is a plan view of a portion of the skirt-attaching frame detached.

A is the spring frame of any suitable construction, provided with a base border wire 30 B, C is the cushion and D the skirt depending therefrom.

To secure the lower end of the skirt to the frame I provide a securing member of U-shaped cross-section, which is engageable 35 with the base border wire B after the skirt is drawn thereover and is then clenched to hold the same from disengagement. As 40 preferably constructed this securing member D is formed of a sheet-metal strip bent into U cross-section and longitudinally fashioned to conform to the shape of the base border wire. Portions of the inner flange of this member D are cut away, as at E, to 45 clear the connection between the base border wire and the spring supporting base. As shown the base is formed of cross strips F secured to the springs G and at their ends bent about the wire B. The cut-away por-

tions E of the member D will permit of forcing said member over the border frame 50 B and clamping the skirting intermediate the same. The portions H of the member C which are intermediate the cut-away portions are then bent or clenched by any suitable tool and will thereby hold the member 55 from disengagement.

With the construction as described the operation of securing the skirt to the frame is very quickly performed and the portion so secured is protected from wear by the 60 metallic covering.

What I claim as my invention is:

1. In a cushion seat, the combination with a cushion, a spring frame having a base border wire and cross-bars for supporting 65 the springs attached at their ends to said base border wire, of a skirt depending from said cushion and drawn around beneath said base border wire, and a frame formed of a channel strip conforming to the contour of said base border wire, the sides of 70 said strip extending upward and spaced to embrace the border wire and portion of the skirt around the same, the outer side being straight and the inner side being cut away 75 to clear said cross-bars at their points of attachment to said base border wire and the portions of said inner side intermediate said cut away portions being clenched to retain the strip. 80

2. In a cushion seat, the combination with a cushion, a spring frame having a base border wire and cross-bars, the ends of which are secured to said border wire, of a skirt depending from said cushion and drawn around beneath said border wire, and a frame formed from sheet-metal struck up to form a channel cross section, the sides thereof extending upward and being spaced to embrace said base border wire with the skirt 85 thereabout, portions of the inner sides being cut away to clear said cross-bars and the portions intermediate said cut-away portions being clenched. 90

In testimony whereof I affix my signature. 95
JAMES J. WISELOGEL.
